US00D945844S

(12) United States Design Patent (10) Patent No.: US D945,844 S
(45) Date of Patent: * Mar. 15, 2022

(54) SHOPPING CART HANDLE HOLDER

(71) Applicant: NINGBO GECEN PROMOTION & GIFT CO., LTD, Zhejiang (CN)

(72) Inventor: Weijin Ying, Ningbo (CN)

(73) Assignee: NINGBO GECEN PROMOTION & GIFT CO., LTD.

() Term: 15 Years

(21) Appl. No.: 29/740,936

(22) Filed: Jul. 8, 2020

(51) LOC (13) Cl. 08-05

(52) U.S. Cl.

USPC D8/19

(58) Field of Classification Search
